UNITED STATES PATENT OFFICE.

FRANZ SOXHLET, OF MUNICH, GERMANY, ASSIGNOR TO FRANZ O. MAT-
THIESSEN, OF IRVINGTON, NEW YORK.

PROCESS OF MANUFACTURING GRAPE-SUGAR.

SPECIFICATION forming part of Letters Patent No. 335,044, dated January 26, 1886.

Application filed December 2, 1885. Serial No. 184,318. (Specimens)

To all whom it may concern:

Be it known that I, FRANZ SOXHLET, of Munich, Germany, have invented a new and useful Process of Manufacturing Crystallized 5 Grape-Sugar, of which the following is a specification.

The object of this invention is to produce a pure hydrate of grape-sugar in wart-like-formed and compact crystals, which can be 10 effectually drained in the centrifugal machine, so that the resulting product will have a pure saccharine taste, without any bitter or other unpleasant residual flavor. This product is produced by preserving certain prescribed relations between the density of the sugar solution in which the crystals are to be developed and the temperature at which the sugar solution is maintained during the crystallizing operation. 15 These conditions of temperature and density comprise the characteristic features of the process, which constitutes one part of the invention, and the product resulting from the practice of the process under the prescribed conditions constitutes the other part of 20 the invention.

As it is impossible to accurately determine the densities of highly-concentrated sugar solutions at low temperatures, the densities mentioned in this specification are all taken at a 25 temperature of the solution of 194° Fahrenheit, at which temperature the solutions are very limpid and the readings of the saccharometer can be quickly and accurately accomplished.

In carrying out the process the aqueous solution of grape-sugar is concentrated in the vacuum-pan to a density, preferably, of 36½° Baumé taken at 194° Fahrenheit. It is then drawn from the vacuum-pan into a tank or 30 vat and allowed to cool to a temperature of 95° Fahrenheit, at which temperature it is carefully maintained during the process of crystallization, which soon begins, and which continues for a period of about five days. 35 Under these conditions of density and temperature a crystallized hydrate of grape-sugar is formed the crystals of which are wart-like and glassy in their appearance and of a compact structure, and can be perfectly cleaned 40 by being drained in the ordinary centrifugal machine.

The density of 36½° Baumé and the temperature of 95° Fahrenheit are those which are found to be the most effective for dealing with a large quantity of grape-sugar. They 55 permit the use of crystallizing-tanks of any desired large capacity.

Results of an analogous character can be produced from a sugar solution of a higher density than 36½° Baumé; but if the sugar is 60 to be taken from the vacuum-pan at a higher density, it must be held at a higher temperature during the process of crystallization. For example, if the sugar solution has a density of 39° Baumé, it must be held at a temperature of 105° Fahrenheit. In dealing with a solution of 41° Baumé a temperature of 65 113° Fahrenheit may be maintained in the crystallizing tank.

It will be found that the development of the 70 wart-like formed and compact crystals of hydrate of grape-sugar depends upon the preservation, within comparatively narrow limits, of certain relations between the densities of the sugar solution and the temperatures at 75 which the sugar solutions are respectively maintained during the crystallizing operation. The present invention is based upon this broad generalization, and it is therefore not intended that it should be understood that 80 the invention is limited to either one of the precise densities stated, nor to either one of the precise temperatures stated, provided that the rule governing the temperature during the crystallizing operation relatively to the density be substantially such as herein set forth.

The density of 36½° Baumé is preferred, because with greater concentration there is produced more or less anhydrous grape-sugar. As the object of the process is to produce crystalline hydrate, the density of 36½° Baumé 85 may be taken as indicating the highest degree of concentration desirable. It is also to be remarked that with a lower temperature for the crystallizing-tank containing a solution of the specified density—36½° Baumé—the resulting product will be soapy hydrate, which is 90 unfit for any refining operations, instead of the wart-like-formed, glassy, and compact crystals which it is the object of this process to produce, and which can be easily and completely 95 drained and cleansed in a centrifugal machine.

After the formation of crystals has ceased, which will be in about five days, if the solution be of a density of 36½° Baumé, and if the temperature in the crystallizing-tank is 5 carefully preserved at 95° Fahrenheit, the crystalline hydrate is removed from the crystallizing-tank and drained in the ordinary way in the centrifugal machine. It will be found that the resulting product is a pure 10 crystalline hydrate having a saccharine taste and entirely free from any bitter or other unpleasant flavor.

What is claimed as the invention is—

1. The herein-described process of manufacturing 15 hydrate of grape-sugar in crystals of wart-like and compact form and glassy ap-

pearance, which consists in introducing into a suitable crystallizing-tank an aqueous solution of grape-sugar of a density of 36½° Baumé, determined at 194° Fahrenheit, and 20 maintaining it at a temperature of 95° Fahrenheit during the crystallizing operation.

2. Pure hydrate of grape-sugar crystallized in wart-like and compact forms and of a glassy appearance, produced by the process herein 25 set forth.

FRANZ SOXHLET.
